UNITED STATES PATENT OFFICE.

HERBERT EDWARD PRICE, OF SEATTLE, WASHINGTON.

ANIMATED TOY.

Application filed September 6, 1927. Serial No. 217,779.

This invention relates to an animated toy and is designed more particularly as an improvement upon the structure disclosed in my co-pending application filed January 29, 5 1927, Serial No. 164,561.

One of the objects of the invention is to simplify the mechanism utilized for actuating the eyes, ears and tongue of the animal simulated by the toy and to simplify and 10 otherwise improve upon the leg operating mechanism.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within 20 in the scope of what is claimed, without departing from the spirit of the invention.

In the accompanying drawings, the preferred form of the invention has been shown.

In said drawings,

25 Figure 1 is a top plan view of the toy, the body portion being shown in section to illustrate the propelling mechanism therein.

Figure 2 is a view partly in side elevation and partly in section of the complete 30 toy.

Figure 3 is a central longitudinal section through the head portion.

Figure 4 is a horizontal section through the head portion.

35 Figure 5 is a detail view of one of the eyes and adjacent parts.

Figure 6 is a detail view of one of the ear members and adjacent parts.

40 Figure 7 is an enlarged transverse section through the tongue mechanism.

Referring to the figures by characters of reference 98 designates the head portion of the top pivotally connected, as at 99, to brackets 100 extending forwardly from the body 45 portion 101. It is to be understood that this body portion and the head will be provided with a suitable covering whereby the toy will simulate some animal. Pivoted in openings 102 and 103 in the bottom portion of the 50 body are the upper leg members 104 and 105 of the front and rear legs respectively, these members being in the form of levers fulcrumed as indicated at 106. A spring motor 107 is mounted in the body and drives a 55 double crank 108 connected to pitmans 109

and 110 extending in opposite directions within the body. Pitman 110 is connected to the upper end of the leg member 105 while pitman 109 is connected to an extension 111 at the upper end of the leg member 104. A 60 cross lever 112 is fulcrumed at 113 in the front portion of the body and one end of this lever engages the extension 111 of one of the front legs while the other end of the lever engages the corresponding extension of the other front leg. A similar cross lever 65 114 is provided in the rear portion of the body for connecting the upper portions of the rear legs. Thus the two front legs will swing in opposite directions respectively and the 70 same is true of the two rear legs, all of the legs being actuated by the pitmans 109 and 110 from the crank 108. The lower members 115 of the front legs are pivotally connected to the upper members at 116 and have feet 75 117 hingedly connected to the lower ends as shown at 118. Stops 119 are provided adjacent the hinges for limiting the movement of the feet. A similar construction is provided at the lower end of each of the rear legs. 80 Arms 120 are extended upwardly from the members 115 and are connected by rods 121 to a lever 122 which, in turn, is connected by rods 123 to arms 124 extending upwardly from the lower members of the rear legs. 85 Thus when the motor is in operation the legs will be actuated to cause the toy to move forwardly as will be obvious. An upstanding lever 125 is connected by a rod 126 to the upper portion 105 of one of the legs and this 90 lever is also connected by a rod 127 to one side of the head 98 as shown at 128. Consequently as the toy moves forwardly the head will be caused to swing laterally relative to the body. 95

The head 98 is provided with a hinged lower jaw 129 connected to the head as shown at 130 and provided, in its upper face, with a longitudinally extending dovetail 131 engaged by a slide 132. This slide is shaped to simulate a tongue and is normally drawn forwardly by a spring 133 housed in the dovetail 131. A yoke 134 straddles the rear portion of the tongue and is connected to the rear portion of the jaw which is in the form of a rear extension of the dovetail 131. A spring 135 connects this yoke 134 to the top of the head and thus tends to hold the jaw 129 normally swung downwardly at its front end so as to simulate an open mouth. A cord in- 105 110 115 120 125 130 135

dicated at 136 is attached to the rear portion of the tongue and extends through one or more guides 137 to the extension 111 on one of the front legs. Thus it will be seen that as this front leg swings relative to the body it will successively pull and then release cord 136 with the result that tongue 132 will be swung backwardly and released and at the same time be swung downwardly and thence upwardly. When the cord is released springs 133 and 135 will return the parts to their initial positions but when the cord is pulled these springs will be elongated.

Openings 138 are provided in the head 98 for the eye balls 139. These balls are supported by bearing pins 140 and arms 141 extending inwardly therefrom. Each arm is connected by a rod 142 to the inner end portion of a lever 143 pivotally mounted within and extending outwardly from the head 98 as shown clearly in the drawings. Another rod 144 is extended from the inner end of each lever 143 and attached to the body 101 close to the head. Thus it will be seen that during the forward movement of the toy as heretofore explained the head will be swung laterally and each time it swings laterally the rods 144 and 142 will cause the levers 143 and the arms 141 to swing. Consequently the coverings of the outer ends of levers 143 which simulate ears will be caused to wag while the balls 139 which simulate the eyes will rotate.

What is claimed is:

- 35 1. In an animated toy the combination with a body, and means for propelling the body,

said means including pivoted leg members and a clock mechanism for operating the leg members, of an upstanding lever, a rod connection between said lever and one of the leg 40 members, a laterally movable head connected to the body, a rod connecting said upstanding lever to one side of the head, for swinging the head laterally when the lever is actuated, eye balls exposed within the head, ear levers fulcrumed within and extending from the head, inwardly extending arms upon the eye balls, connecting rods between said arms and the respective ear levers, connecting rods between said ear levers and the body, and 50 coverings on the projecting portions of the ear levers simulating ears.

2. In an animated toy the combination with a body and means for propelling the same forwardly, said means including pivoted leg 55 members and a clock mechanism for operating the leg mechanism, of a head mounted to swing laterally relative to the body, means for transmitting motion to the head from one of the leg members, eye balls rotatably mounted in the head, inwardly extending arms thereon, ear levers fulcrumed within and extending outwardly from the head, rods connecting the arms to the respective ear levers, rods connecting the ear levers to the body, and means for swinging the head laterally to shift the same relative to the points of connection between the rods and the body, thereby to actuate the ear levers and the eye balls. 60

In testimony that I claim the foregoing as 70 my own, I have hereto affixed my signature.

HERBERT EDWARD PRICE.
